UNITED STATES PATENT OFFICE.

CHARLES BABCOCK, OF SALT LAKE CITY, UTAH, ASSIGNOR OF ONE-THIRD
TO BOYD PARK, OF SAME PLACE.

PENCIL-SHARPENING DEVICE.

SPECIFICATION forming part of Letters Patent No. 658,824, dated October 2, 1900.

Application filed March 30, 1900. Serial No. 10,791. (No model.)

To all whom it may concern:

Be it known that I, CHARLES BABCOCK, of Salt Lake City, county of Salt Lake, and State of Utah, have invented new and useful Improvements in Pencil-Sharpening Devices, of which the following is a specification.

My invention relates to pencil-sharpener; and my improvements upon this class of devices have for their object the production of a construction whereby they are made more efficient for the purposes for which they are designed.

Accompanying this specification to form a part of it there are two plates of drawings containing four figures illustrating the application of my invention, with the same designation of parts by letter reference used in all of them.

Of the illustrations, Figure 1 is a side elevation of the apparatus with the pencil-holder and its clutch in a position to have a pencil inserted therein. Fig. 2 is another side elevation of the device with a part of the wall by which the working parts are inclosed illustrated as broken out. Fig. 3 is a top view of the mechanism. Fig. 4 is a vertical section taken on the line $\alpha\alpha$ of Fig. 3.

The several parts of the apparatus thus illustrated are designated by letter reference, and the function of the parts is described as follows:

The letter K designates the case in which the mechanism is inclosed and mounted, and this case has a circular form, having its sides made to taper slightly inwardly as extended upwardly.

The letter A designates a plate that is transversely arranged within and secured to the case-walls at a^1 a^2 a^3 and is preferably constructed to have a triangular form.

The letter J designates a vertically arranged bearing formed centrally in the plate A and in which the cutting mechanism is arranged to journal. This bearing J is extended downwardly from the bottom of the plate A in a connected tube-form extension a^3 , as shown at Figs. 2 and 4.

The cutting mechanism consists of a disk D, having radially projected from its perimeter a series of cutting-blades B, and which disk is provided with a shaft S, that is down-

wardly projected from the under side of the disk, so as to enter and journal within the vertical tube-form bearing J, depending from the under side of the horizontally-arranged plate A, with the upper end of the shaft S projected upwardly through the disk D and thereat provided with an operating-crank C², thereat secured by the nut O.

The letter a^1 designates a collar that is upwardly projected from the top of the cross-plate A to encircle the bearing J, and the letter d^2 designates an annular recess formed in the under side of the disk D, adapted by its form and location to receive the collar a^1 . Each of the cutting-blades B is at its inner end secured in the perimeter of the disk wheel D, with its cutting edge e^2 projecting downwardly on an angle which is acute to the top of the disk wheel D, with the outer ends e^3 of the blades projected upwardly and their upper surface made slightly concave in cross-section, as indicated at e^4 .

The letter b^2 designates a pintle-shaft which is arranged to depend from the under side of the plate A, and the letter T designates a tube arranged upon said pintle-shaft and free to turn thereon, said tube being retained in position on said pintle-shaft by a pin p' , passing transversely through the shaft b^2 where the latter extends below the end of the tube T, on which pin so placed the lower end of the tube T rests.

The letter E designates an arm which is rigidly connected to said tube T and laterally projected therefrom. The letter l designates a pin that is projected upwardly from the outer end of said arm E, where the upper end of said pin will be in a position to actuate the tube T to be reciprocatingly rotated on said pintle-shaft as said pin successively comes in contact with the blades of the cutting mechanism.

The letter P designates a pawl which at its inner end is connected to the tube T, and at its outer end the arm of this pawl is arranged to pass out of the case through a slot horizontally formed therein, as indicated at l^2 . As operated by the reciprocation in rotation of the tube T and the movement of the arm E, this pawl P is actuated to engage with the perimeter of the ratchet-wheel R on the outer

end of the pencil-holder V, and thus actuate the latter to move one tooth each time one of the blades B comes in contact with, so as to move outwardly, the pin l.

- 5 The letter I designates a spring which at its lower end is connected to the exterior of the tube-form bearing J, and from this connection it is helically coiled around said bearing, with its outer end attached to the pawl P at i², against the force of which spring the said pawl is operated and returned to position after being actuated.

The pencil-holding mechanism H consists of a tube-form inclosure h², which is secured 15 to and projected from the side of the case K, as indicated at Figs. 1 and 3.

- 15 The letter L designates a tube-form shaft which is arranged within the tube-form inclosure h² and constructed to be rotated 20 therein by means of the ratchet-wheel R and the pawl P, operated as before described. This tube-form shaft L is retained in place within the inclosure h², in which it journals, by means of a groove g, formed to exteriorly 25 encircle said tube-form shaft L, and a spring-pin p⁴, mounted exteriorly upon the tube-form bearing or inclosure h². This spring-pin has a C form arranged to encircle exteriorly part of the tube-form bearing h², with 30 one of its ends attached to the latter and the other free end of the spring part provided with a pin p⁴, adapted to pass through an opening in the tube-form bearing to enter the groove g, as shown at Fig. 4, thus permitting the free revolution of the tube-form shaft L, and by the engagement of the pin with the slot g to prevent its outward movement. This tube-form shaft L is slightly expanded at its inner end, as indicated at n².
- 40 The letter V designates the pencil-holder proper, and it consists of a tube which is open at both of its ends, and it is arranged within the tube-form shaft L. The outer end of this pencil-holder proper is provided 45 with a series of slits that are extended from the end of the holder inwardly and thereat provided with a lip f'. The outer end of this holder proper is also slit inwardly and is thereat slightly drawn inwardly.

- 50 The letter C designates a clutch which at c⁵ is pivoted to the side of the pencil-holder proper where extending outwardly beyond the end of the tube-form shaft L, and the letter c⁶ designates a cam formed on the inner end of the clutch.

- 55 The letter h⁴ designates the clutch-handle, and which when pulled outwardly engages with the outer face of the ratchet-wheel R and draws outwardly the holder proper, causing 60 its inner slotted end to engage with the expanded inner end of the tubular shaft L, and thus cause the inwardly-forced end and slotted parts of the holder proper to rigidly grasp and hold an inserted pencil, aided by 65 the grasping action of the slotted and in-turned end parts at the outer end of the holder proper.

The letter N designates a slide-bar which is horizontally placed immediately beneath the vertical shaft S of the cutting mechanism and upon which bar the lower end of said shaft rests. This slide-bar N is adapted to be moved inwardly and outwardly in slots n⁵ and n⁶, formed in the case sides, with the operating end of this bar N projecting beyond the case at K².

The letter r⁵ designates a spring arranged to encircle the bar N between the wall of the case and the shoulder r⁶, formed on the bar N, against the resiliency of which the bar N is moved inwardly.

The letter R² designates a recess formed in the upper face of the bar N, said recess having the vertical end r and the inwardly and downwardly inclined end r³ and between these ends the horizontal part r⁴.

As thus constructed, a pencil being inserted within the holder proper, so that the end to be sharpened will be over that part of the plate A designated at a⁶ in Fig. 3, the clutch 90 is operated to grasp the pencil, as before described. This having been done, the crank is operated to actuate the cutting mechanism, and so soon as the cutting commences the bar N is moved inwardly slowly, while the shaft 95 S is slowly passing down along the incline r³. The cutting continues to operate in a plane lower than at the start until the bottom end of the shaft S reaches the bottom of the recess R², and so soon as the inward pressure 100 upon the bar N ceases the spring r⁵ becomes active to move outwardly the bar N. While the cutting mechanism is being rotated, its blades successively in passing with each engage with the pin l on the crank-arm E to 105 rotate the tube T, and thus actuate the pawl P on the latter to operate the ratchet-wheel R to rotate the pencil-holder proper.

The blades B are located with reference to the operation of the pawl P and ratchet-wheel R, so that the blades will only cut 110 when the pencil is at one of its periods of rest and the blades B will only engage with the pin l, between the intervals that the blades are cutting.

By having the plates of the cutting mechanism slightly concave on their upper face and so positioned in the disk-perimeter that their outer ends will project upwardly on an incline, with their cutting edges extended 120 downwardly from the plane of their rotation and being operated to cut only when the pencil-holder and pencil are at rest, and then in the direction of the grain of the wood, the blades by their position and form, as thus 125 described, will give to the pencil-point a conical form that is slightly concave. As thus constructed the cutting mechanism can be removed for sharpening the blades when necessary.

As the cutting mechanism herein shown and described would perform the same function in the same manner in connection with any pencil-holding mechanism which would

operate the pencil relatively in the same manner, hence I do not limit my invention of the cutting mechanism herein described to its combination with the pencil-holding mechanism which I illustrate and describe.

Having thus described my invention, what I claim, and desire to secure by Letters Patent, is—

1. In a pencil-sharpener the combination with the case K, having in its side the oppositely-formed slots n^5 , and n^6 ; of the plate A, having the downcast bearing J; the disk D, provided with the blades B, radially arranged thereon, and the downwardly-projected shaft S; the bar N, arranged to be moved outwardly and inwardly in the slots in the case sides and provided with the recess R², constructed with the inclined side r³, and vertical end r²; and the spring r⁵, constructed and arranged to be operated substantially as, and for the purposes set forth.

2. In a pencil-sharpener the combination with the case K, having the transversely-arranged plate A, provided with the depending bearing J; of the disk D, having the blades B, radially arranged on the perimeter thereof, each projected upwardly on an incline and having its cutting edge arranged to project downwardly, with its shaft S, arranged in the bearing J; the pintle-shaft b², depending from the plate A; the tube T, arranged to turn on said pintle-shaft, and provided with the laterally-extended arm E, having the upwardly-projected pin l; the pawl P, laterally projected from said tube T; and the pencil-holding mechanism H, provided with the ratchet-wheel R, constructed and arranged to be operated substantially as, and for the purposes set forth.

3. In a pencil-sharpener the combination with a case of a pencil-holder provided with a pencil-grasping clutch, and arranged within a tube-form shaft provided with a ratchet-wheel and constructed to journal in a tube-form bearing projected from said case; of a plate horizontally arranged in said case and provided with a depending bearing; and a depending pintle-shaft; a tube arranged to

turn on the latter and having a laterally-extended arm provided with an upcast pin; and a pawl laterally projected from said tube whereby to actuate said ratchet-wheel; and a disk provided with radially-arranged blades and having a shaft arranged to journal in said depending bearing; said blades when the disk is rotated being arranged to operate the connections actuating said pawl, substantially as and for the purposes set forth.

4. The combination with the case K, of the tube h², projected through the latter; of the tube-form shaft L, having its inner end expanded; and the pencil-holder proper V, arranged within the tube-form shaft, and having its ends slit inwardly and its inner end expanded; and the clutch C², having the cam c⁶, and the handle h⁴, and pivoted to said pencil-holder proper, at c⁵, whereby a pencil inserted within said pencil-holder proper is by the combined action of the before-named parts rigidly grasped, substantially as and for the purposes set forth.

5. In a pencil-sharpener the combination with a case, of a horizontally-arranged plate having a tube-form bearing depending therefrom; a wheel having cutting-blades radially projected from its perimeter, and provided with a shaft arranged to vertically journal in said depending bearing; a horizontally-arranged bar provided with slideways in the case-walls on which bar the lower end of the shaft of said wheel is supported; and a recess formed in the upper surface of said bar and provided with an incline whereon the shaft and cutting mechanism may be operated to descend and thus cut in a lower plane substantially as and for the purposes set forth.

Signed at Salt Lake City, Utah, this 12th day of March, 1900, and in the presence of the two witnesses whose names are hereto written.

CHARLES BABCOCK.
